(57) **CLAIM**

The ornamental design for a fuel container, as shown and described.

DESCRIPTION

FIG. 1 is a perspective view of a fuel container showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view; and,

FIG. 8 is another perspective view thereof showing a using condition with the wick.

The broken lines are for the purpose of showing environmental structure and form no Part of the claimed design.

1 Claim, 8 Drawing Sheets
